APPARATUS FOR FILLING AMPOULES

Sidney Ernest Harris, Nutley, and Carl Emil Engel, Glen Rock, N. J., assignors to Hoffmann-La Roche Inc., Nutley, N. J., a corporation of New Jersey

Application November 26, 1949, Serial No. 129,654

16 Claims. (Cl. 226—107)

1

This invention relates to an apparatus for simultaneously filling a plurality of ampuls or like containers with a fluid, such as a medicinal liquid.

It is an object of the invention to provide an improved ampul-filling machine which will fill ampuls at high speed, with a minimum of human intervention and with minimum loss due to improper filling of ampuls. It is a further object of the invention to provide such a machine which is simple in construction, adjustment, operation, and maintenance.

To this end, the invention provides an apparatus which comprises a means for storing fluid, means for withdrawing a measured amount of fluid from said storage means, means for dividing the withdrawn fluid into a plurality of equal portions, and means for transferring each portion into a respective ampul. The apparatus is also characterized by means for preventing the insertion of more than a single charge into each ampul. The apparatus is further characterized by means for avoiding internal wetting of the necks of the ampuls by the fluid with which they are filled; the purpose of this provision is to avoid loss of ampuls during a subsequent step (not performed by the apparatus of this invention) in which the ampuls are sealed by fusing their necks; if the necks are free of fluid, any loss due to charring of the fluid in the necks, or to bursting of the seals by gases formed from the fluid, is avoided. The apparatus is still further characterized by means for preventing breakage of ampuls due to improper insertion of the filling needles. The apparatus is still further characterized by means which permit the adjustment of the device between runs to handle ampuls of differing capacity.

These features and others will become apparent from the following description and the accompanying drawings in which:

Fig. 1 is a top plan view of one embodiment of the invention, with certain parts broken away.

Fig. 2 is a front elevation of the device of Fig. 1, with the upper portion broken away.

Fig. 3 is a diagrammatic drawing, partly in section, showing the arrangement of the elements of the device of Fig. 1.

Fig. 4 is a view of the clutch device, partly in section.

Figs. 5, 6, and 7 are views showing details of the clutch device of Fig. 4.

Figs. 8 and 9 are views, partly in section and with parts broken away, showing details of the pump and the valve device of Fig. 1.

Fig. 37 is a side view, partly in section, of a modified form of filling needle.

Fig. 38 is a cross section along the line 38—38 of Fig. 37, looking in the direction of the arrows.

Fig. 39 is a side view of a modified form of clutch arrangement.

CONSTRUCTION OF THE DEVICE

Referring to the drawings and particularly to the embodiment of the invention shown in Figs. 1 and 3, the filling apparatus comprises a reservoir or source of supply of fluid 1, a pump 2, a motor 3, a valve device 4, and a filler box 5. Broadly, the operation of the filling apparatus is such that the pump withdraws fluid from the

source of supply on its intake cycle and discharges fluid to the filler box, and thus to the ampuls, on its discharge cycle, the valve device regulating both the intake and the discharge.

Considering the fluid lines in greater detail, supply source 1 is connected to valve device 4 by a flexible tube 6, and valve device 4 is connected on the one hand to pump 2 by a flexible tube 7 and on the other hand to filler device 5 by a plurality of flexible valve discharge lines 8. The valve discharge lines 8 are respectively connected, through equalizing valves 9, to flexible needle discharge lines 10 and thus to filling needles 11.

Pump 2 is driven as follows: Motor 3, through reduction gearing 12, drives pinion 13, in mesh with gear 14, rigidly connected to the driving half 15 of a conventional solenoid-controlled pin-operated clutch 16 comprising a driving half 15 and a driven half 21. As appears more clearly in Figs. 3, 4, and 5, driving half 15 rotates freely on a shaft 17 journaled in frame supporting members 18, and is provided with a collar 19, toothed on its inner face as at 20. Driven half 21 of clutch 16 is keyed to shaft 17 and bears a pivoted dog 22 which is normally extended by a spring 23 into engagement with toothed inner face 20 of collar 19, as shown in Fig. 7. A pin 24 integrally connected with the armature of a solenoid 25 normally extends into the annular space between driven half 21 and collar 19 of driving half 15. When extended, pin 24 engages dog 22, as shown in Fig. 5, and forces dog 22 into retracted position, out of engagement with toothed surface 20. When the motor is running, driving half 15 rotates freely on shaft 17, and driven half 21 remains stationary, so long as pin 24 is extended. But when pin 24 is withdrawn, upon energization of solenoid 25, dog 22 is urged by its spring 23 into engagement with toothed surface 20, and the rotation of driving half 15 is imparted to driven half 21 and thus to shaft 17. This rotation continues only so long as dog 22 does not abut pin 24. Pin 24 is only momentarily withdrawn; the pin is then again extended, upon de-energization of solenoid 25; dog 22 is rotated until it is again in abutment with pin 24, as shown in Fig. 7, and the dog is then again retracted against driven half 21 (Fig. 5), and rotation of the latter and of shaft 17 ceases. Therefore, for each withdrawal of pin 24, driven half 21 travels through one complete rotation, but only one. Shaft 17, when it does rotate, serves to rotate an eccentric 26 (Figs. 3, 8, and 9), which is provided with a radial slot 27, in which is adjustably fixed a bearing block 28, to which in turn is pivotally connected a connecting rod 29 attached to the piston 30 of pump 2. Eccentric 26 also has attached thereto a fixed cam 31 and an adjustable cam 32, which lies in a circumferential recess 33 of eccentric 26, and may be adjusted to lie closer to or farther from a center line drawn through the leading edge of fixed cam 31. Cams 31 and 32 are so arranged as to contact switches 109 and 110, respectively, at different times in the cycle of rotation of eccentric 26, as will be explained more fully hereinafter.

The valve device 4 is illustrated particularly in Figs. 1, 10, 11, 12, and 13. Referring to Fig. 11, the valve device comprises a lower disc 33 and an upper disc 34. Lower disc 33 is fixedly secured to the main frame structure of the filling apparatus, as by set screws 35 set against supporting parts 36 of the main frame. Lower disc 33 is provided on its lower face with a chamber or manifold 37, sealed by a plate 38 secured to

lower disc 33 as by screws 39. A port 40 communicates with the lower part of manifold 37 at its center, and a passageway 41 communicates with manifold 37 at a point near its circumference. Lower disc 33 is bored out on its upper face to provide a valve seat 42. At the center of its upper face, lower disc 33 is provided with a fixed stud 43, and on the stud is rotatably mounted upper disc 34 on a bushing 44. A cap screw 45 maintains the upper disc in contact with the lower disc. The pressure of contact between the upper and lower discs is controlled by the setting of set screws 46, which are mounted in brackets 47 secured to lower disc 33 as by screws 48. A positioning pin 49 is provided to assist in positioning bracket 47 on lower disc 33 during assembly of the parts. Upper disc 34 is further provided on its lower surface with an abutment 50, which mates with and seats in valve seat 42. An anti-friction liner 51 of soft metal is fixed to the lower surface of abutment 50, and the surface of contact between the liner and valve seat 42 is suitably lubricated. A circumferential groove 52 in the valve seat is provided to collect excess lubricant.

Upper disc 34 is also provided with a passageway 53 and a corresponding valve intake port 54 on the upper surface of the disc. A mating passageway 55 is provided in liner 51. In the relative position of the upper and lower discs illustrated in Figs. 10 and 11, passageways 53 and 55 and port 54 are in register with passageway 41 in lower disc 33, but upon partial rotation of the upper disc as illustrated in Figs. 12 and 13, passageways 53 and 55 and port 54 are brought out of register with passageway 41. Upper disc 34 is further provided with a plurality (sixteen in the embodiment shown, corresponding in number to the number of filling needles in the filler box, to be hereinafter described) of passageways 56 and corresponding valve discharge ports 57. A plurality of mating passageways 58 are provided in liner 51. In the relative position of the upper and lower discs shown in Figs. 12 and 13, passageways 56 and 58 and ports 57 are respectively in register with a plurality of corresponding passageways 59 in lower disc 33 communicating with manifold 37, but upon partial rotation of the upper disc to the position shown in Figs. 10 and 11, passageways 56 and 58 and ports 57 are brought out of register with passageways 59. It will be apparent, then, that when the parts 41, 53, 54, and 55 are all in register, the parts 56, 57, 58, and 59 are out of register (Figs. 10 and 11), but conversely, when the parts 56, 57, 58, and 59 are in register, the parts 41, 53, 54, and 55 are out of register (Figs. 12 and 13).

Flexible intake tube 6 is connected to valve intake port 54, and flexible valve discharge lines 8 are connected to respective valve discharge ports 57.

Fixed to an arc of upper disc 34, as by screws 59, is a sector gear 60, in mesh with a rack 61 mounted to reciprocate in a guide 62. The guide 65 is secured to the main supporting frame of the device, as by threaded rods 63 and nuts 64. As shown more particularly in Figs. 1 and 3, one end of rack 61 is integrally connected with the common armature 65 of a pair of solenoids 66 and 67. These are so arranged that upon energization, solenoid 66 pushes the armature toward the valve device, while solenoid 67 upon energization pushes the armature away from the valve device.

Considering now the filler box in greater de-

tail. This comprises a box-like frame 68 fixed to the main supporting structure of the filling apparatus (Figs. 3 and 19). Journalized in cross-members of frame 68 is a shaft 69 which carries a pair of gears 73 adjacent to and interiorly of the side walls of frame 68. Shaft 69 is extended exteriorly of frame 68 and has secured thereto at the exterior end an operating handle 71. A second shaft 72 is journalized in cross-members of frame 68, and carries at its ends a pair of gears 73, which mesh with respective gears 70.

The main supporting structure includes a pair of vertically disposed guides 74 (Fig. 14) in which are slidably mounted a pair of racks 75, extending upwardly into the interior of frame 68. At their upper ends, racks 75 are toothed as at 76 to mesh with gears 73. Fixed to racks 75, as by brackets 77, is a horizontal riser plate 78, disposed for up-and-down movement in an opening 79 in front panel 80 of frame 68. Exteriorly of front panel 80, riser plate 78 carries an inverted L-shaped angle 81, the horizontal leg 82 of which is notched as at 83 (see Fig. 21) for a purpose to be hereinafter explained. The notches are aligned with respective filling needles 11, as shown in Fig. 2. Along its front edge, riser plate 78 carries a hinge-flap comprising a cylinder 84, eccentrically hinged as at 85 (see Fig. 15) and provided at its ends with a pair of arms 86 (Fig. 2) to support a striker bar 87 parallel to cylinder 84.

A yoke 88, hung above L-angle 81, as by hangers 88' (see Figs. 2 and 14) supports a plurality (sixteen, in the embodiment illustrated) of generally cylindrical ampul guides 89, slideable for up-and-down movement in yoke 88. The bottom faces of ampul guides 89 are countersunk, as shown at 90, and the countersinks communicate with central bores 91 in the guides 89. An upper yoke 92, secured to front panel 80, supports hangers 88' and a plurality of filling needles 11 (sixteen in the embodiment shown) which pass into central bores 91. When ampul guides 89 are in lowermost position (Fig. 14) the ends of needles 11 do not extend into countersinks 90, but when the ampul guides are raised (Fig. 17) the needles extend lower than the countersinks.

Frame 68 also includes a top panel 93, which supports a top yoke 94 wherein are mounted equalizing valves 9, one for each filling needle 11. A pair of stop rods 95 and 96, threaded at their upper ends, are adjustably mounted, as by lock nuts 97, at the approximate center of the top panel 93 (see Fig. 15).

Riser plate 78 at its rear edge is provided with a pair of anti-friction rollers 98 (Fig. 19), and is also provided with two switches 99 and 100. Switch 99 is normally open and is provided with a spring-loaded button 101 which closes the switch so long as it is depressed, as by contact with the rear stop rod 96 (Fig. 16). Switch 100 is provided with a top button 102, which opens the switch when depressed, as by contact with front stop rod 95 (Fig. 17), and is also provided with a bottom button 103, which closes the switch when depressed, as by contact with a bottom stop 104, provided in the bottom panel of frame 68. The switches are electrically connected with sliding contacts 105, which slide along contact bars 106, provided in the rear panel of frame 68. By means of these contacts, switches 99 and 100 are electrically connected to other electrical parts

of the device, as will be explained in detail hereinafter.

OPERATION OF THE DEVICE

The operation of the device may be explained as follows: For convenience in handling, the ampuls to be filled are loaded into trays, and conveniently each tray will contain a number of ampuls corresponding to the number of filling needles (sixteen in the embodiment shown), as shown in Fig. 20. A sufficient number of trays for steady feeding is maintained at one side of the machine, conveniently the left side as seen in Fig. 1. The operator, seated in seat 107, slides the loaded tray onto riser plate 78 (which is now at the bottom of its travel, as shown in Fig. 14) between L-angle 81 and cylinder 84 of the hinge flap (see Figs. 21 and 23). The operator then raises the hinge flap toward vertical position; eccentrically mounted cylinder 84 thus moves the tray toward the vertical leg of L-angle 81, and striker bar 87 contacts the necks of the ampuls and urges them into respective notches 83 in horizontal leg 82 of L-angle 81 (Figs. 22 and 24). The ampuls are thus positioned under respective filling needles 11. Now, the operator pulls handle 71 towards her, and gears 70 rotate gears 73 to elevate racks 75 and thus to elevate the riser plate. The necks of the ampuls are thereby brought into registration with respective countersinks 90, which serve to center the ampul necks with relation to respective filling needles 11. As the riser plate continues to rise, the ampul guides are forced upwards and filling needles 11 pass into the necks of the respective ampuls, see Fig. 15; at this time the operator moves the hinge-flap back to the position shown in Fig. 15. The exact position of needles 11 in yoke 92 is so adjusted, as by set screws 107, that when riser plate 78 is at the top of its travel, the ends of the filling needles extend just below the constrictions in the necks of the respective ampuls, as shown in Fig. 25. It will be evident that, by means of the L-angle, the hinge-flap and the ampul guides, accidental breakage of ampuls by the filling needles is avoided.

When the ampuls have been filled, by the operation of the machine shortly to be described, the operator pushes handle 71 back, away from her, and the riser plate moves to its bottom position. The operator then slides in a second tray of ampuls from the left, which has the effect of pushing the tray of filled ampuls onto a conveyor belt 108 (Fig. 2), by means of which the tray of filled ampuls is carried to a suitable sealing device (not part of the invention) for sealing the necks of the ampuls by fusing said necks.

The operations of the machine which transfer fluid from the supply source to the ampuls may best be understood from a consideration of Figs. 3 and 27 to 33. Motor 3 is controlled by a main switch 125 in the power line, and the motor therefore operates continuously while the machine is being used. Solenoid 25 which controls clutch 16 is itself controlled by the two switches 99 and 100; since these are connected in series with each other, it is apparent that solenoid 25 will be energized only when switches 99 and 100 are both closed. Solenoid 66 is controlled by switch 109 and is energized only during the period that switch 109 is closed, i. e., during contact of cam 31 with the button of the switch. Similarly, solenoid 67 is energized only during closure of switch 110, that is, during contact of cam 32.

The cycle of operation of the device may be traced in Figs. 27 to 33. Fig. 27 represents the starting point in the cycle: Operating handle 71 is all the way back; the riser plate is all the way down. Solenoid 25 is not energized, consequently pin 24 is extended and clutch 16 is disengaged. Eccentric 26 is stationary, and the fixed cam 31 is some distance away from contact with its switch 109. Upper valve disc 34 is so positioned that the pump is connected to the supply source. The pump piston is just short of the bottom of its stroke. The motor is running, but all other parts of the device are stationary, and this may be considered the "idling position" of the machine.

Now, when the operator pulls the handle towards her (Fig. 28) the riser plate begins to rise. The normally open switch 99 is closed; since switch 100 is also closed, current flows to solenoid 25, as indicated by the heavy black circuit lines, and pin 24 is withdrawn. The clutch engages, and permits the motor to rotate the eccentric; cam 31 is thus brought into contact with switch 109 and the circuit through the latter is closed, thus energizing solenoid 66, as indicated by the heavy black circuit lines. Rack 61 is pushed toward the valve, thus rotating upper valve disc 34, so that the pump is at this point connected to discharge lines 8 and thus to the filling needles; the pump piston is at the very bottom of its stroke, ready to begin its discharge cycle.

Fig. 29 shows the condition an instant later: The riser plate has risen to its top position. Switch 100, which was previously closed, is now opened by contact with front stop rod 95. The circuit to solenoid 25 is opened, the solenoid is de-energized, and pin 24 is again extended. However, since dog 22 is now past pin 24, the clutch remains engaged. Eccentric 26 is rotated further so that cam 31 is now past its contact with switch 109. The circuits to solenoids 66 and 67 are open and the solenoids are not energized. The rack remains stationary, and upper disc 34 remains in the same position as in Fig. 28. The pump piston begins its discharge stroke and fluid flows out of the discharge lines and needles 11 into the ampuls.

In Fig. 30, the operating handle is still all the way forward, and the riser plate is still at its top position, with the ampuls in filling position. Switch 100 is still open, and no current flows to solenoid 25, so that pin 24 remains extended; but since dog 22 is now past pin 24, the clutch remains engaged. Eccentric 26 is rotated further, so that cam 32 approaches its contact with switch 110. The circuits to solenoids 66 and 67 are open and the solenoids are not energized. The rack remains stationary, and upper disc 34 remains in the same position as in Fig. 28. The pump piston has reached the very top of its discharge stroke and fluid has just ceased flowing from the filling needles, but a drop of fluid remains at the tip of each filling needle, as shown in Fig. 25 and diagrammatically at 11 in Fig. 30.

In Fig. 31, the positions of the operating handle, the riser plate and switches 99 and 100 remain the same as in Fig. 30. No current flows to solenoid 25, and pin 24 remains extended. However, dog 22 is now past the pin and the clutch remains engaged; thus eccentric 26 continues to rotate, and cam 32 is now about to contact switch 110. However, the circuits to solenoids 66 and 67 are still open and the solenoids are not energized, so that the rack remains stationary and

upper disc 34 remains in the same position as in Fig. 28, that is, the pump is still connected to the needle discharge lines. The pump piston now begins its return stroke, thus creating suction in the discharge lines so that the liquid at the tips of the filling needles is "sucked-back," as indicated diagrammatically at 11 in Fig. 31. The importance of the "suck-back" operation is that no excess liquid remains on the filling needles to wet the necks of the ampuls as these are withdrawn from the needles.

In Fig. 32, the positions of handle 71, riser plate 18, switches 99 and 100, and pin 24 remain unchanged. Clutch 16 remains in engagement, and eccentric 26 continues to rotate, thus bringing cam 32 into momentary contact with switch 110, and closing the circuit to solenoid 67, as indicated by the heavy black circuit lines. Rack 61 is now pulled away from the valve device, thus rotating upper disc 34 so that pump 2 is now connected to the source of supply through intake line 6. The pump piston continues its return stroke and commences the intake of fluid into the cylinder from the source. By this time the "suck-back" has been completed, as indicated in Fig. 26 and diagrammatically at 11 in Fig. 32.

Fig. 33 indicates the next step. The operator, hearing the click due to the shift of upper valve disc 34 (Fig. 32) knows that the filling step has been completed and that intake from the source has begun; she therefore pushes operating handle 71 away from her, thus beginning the lowering of riser plate 18 with its tray of filled ampuls. As the riser plate is lowered, switches 99 and 100 are brought out of physical contact with their respective stop rods 96 and 95. Spring-loaded button 101 of switch 99 now flies up and switch 99 is again open. Switch 100 remains open, since its top button 102 remains depressed. Both switches being open, no current flows to solenoid 25, and pin 24 remains extended. However, the clutch remains engaged and eccentric 26 continues to rotate, now taking cam 32 farther away from switch 110 and bringing cam 31 closer to switch 109. Switches 109 and 110 are open, no current flows to solenoids 66 and 67, rack 61 remains stationary, upper valve disc 34 remains in the same position as in Fig. 32, that is, the pump is connected to the supply source, and the pump piston continues its return stroke and its intake of fluid from the supply source. No liquid is discharged from the filling needles.

Fig. 27 represents the end of the cycle of operation, as well as the beginning. Operating handle 71 is now all the way back, and riser plate 18 is now at the bottom of its travel. Bottom button 103 has contacted bottom stop 104, thus closing switch 100. However, switch 99 remains open, and therefore no current flows to solenoid 25, so that pin 24 remains extended. Dog 22 has now contacted pin 24 and has been retracted, so that clutch 16 is again disengaged. Eccentric 26 is stationary, with both cams 31 and 32 out of contact with their respective switches 109 and 110. Solenoids 66 and 67 are not energized, rack 61 is stationary, valve disc 34 also remains in the same position, and the pump is connected to the supply source. The pump piston is almost at the bottom of its stroke and the intake of fluid is almost completed. Only the motor is now running, the pump and the eccentric are stationary, and the machine is at the "idling position." It is at this time that the operator slides in a fresh tray of unfilled ampuls, thus pushing the tray of filled ampuls onto the conveyor belt (Fig. 2).

9
MODIFICATIONS

The invention may be embodied in devices other than the particular embodiment described above. Another form of the invention is illustrated diagrammatically in Fig. 34, and may be considered a modification of the device of Fig. 3. In the device of Fig. 3, the intake valve, the manifold, and the discharge valve are incorporated into a single structure, i. e., valve device 4; but in the modification of Fig. 34, these functions are separated. In the modification of Fig. 34, intake of fluid into the pump and discharge of fluid from the pump are controlled by a three-way valve 201, which is operated by a rod 202 connected to common armature 65 of solenoids 66 and 67. The manifold is a separate structure and may take the form of a tubular chamber 203, closed at one end by a cap 204 and at the other end by a suitable filtering device 205. A manifold feed line 206 conducts fluid from three-way valve 201 to filter 205, and a plurality of manifold discharge lines 207 conduct fluid from the manifold to respective equalizing valves 9, thence to respective needle discharge lines 208 and needles 11. A line 209 conducts fluid from a source of supply to three-way valve 201, and a line 210 conducts fluid between said valve and pump 2.

At the instant represented in Fig. 34, valve 201 is in intake position, the pump piston is at the bottom of its stroke, the pump cylinder is full, fixed cam 31 is just ahead of the point of contact with switch 109, and therefore solenoid 66 is about to be energized. In the arrangement of Fig. 34, solenoid 66, when energized, throws three-way valve 201 into discharge position, in which pump 2 is connected to manifold 203. After solenoid 66 has been energized and the valve has moved to discharge position, the pump piston moves to the top of its stroke, forcing fluid through filter 205 into manifold 203 and thus into discharge lines 207. The pump piston then starts its return stroke, "suck-back" of fluid from needles 11 occurs, and at the instant when adjustable cam 32 contacts switch 110, "suck-back" is completed, solenoid 67 is energized, throws valve 201 into intake position, and the pump cylinder is filled from the source of supply.

In the modification of Fig. 34 the discharge cut-off valve is between the pump and the manifold (not between the manifold and the filling needles, as in the embodiment of Fig. 3). Therefore, in the device of Fig. 34, there is no positive cut-off between the manifold and the filling needles. At the end of "suck-back," the liquid level in discharge lines 208 must be above the liquid level in manifold 203, or otherwise the fluid in the manifold would siphon out of the manifold through the discharge lines and the filling needles. For this reason, lines 208 are formed into "goosenecks," or elevated bends, 211, and the relationship of cam 32 to cam 31 is so adjusted that the liquid level 212 in "goosenecks" 211 at the end of "suck-back" is above the liquid level in manifold 203 (see Fig. 34 and detail in Fig. 35).

In the modification illustrated in Fig. 36, the intake and the discharge cut-off valves are embodied in a three-way valve 300, but the manifold is part of a valve device 301, which also embodies in the same unitary structure manifold discharge cut-off valves between the manifold and respective discharge lines 8. In the modification of Fig. 36, valve device 301 is essentially similar to valve device 4 illustrated in Figs. 11 and 13, except that port 54 and passageways 41, 53, and 55 are eliminated, their function being

10

served by three-way valve 300. Valve device 301 comprises an upper and a lower disc, the lower disc being formed with a manifold 31, a port 40, and a plurality of passageways 59 as in the device of Figs. 11 and 13, but lacking passageway 41 of the device of Figs. 11 and 13. The upper disc is formed with a plurality of passageways 56 and ports 57, which may be brought into or out of register with corresponding passageways 59 in the lower disc, but the upper disc lacks the structures 53 and 54 found in Fig. 11. Anti-friction liner is attached to the upper disc, and has passageways 58, corresponding with respective passageways 56, but lacks passageway 55 of the liner of Fig. 11. A line 302 conducts fluid from three-way valve 300 to valve device 301, a line 303 conducts fluid from the source of supply to three-way valve 300, and a line 304 conducts fluid between three-way valve 300 and pump 2. Valve 300 is shifted by a sector gear 305, which is in mesh with a rack 306 rigidly connected to the common armature 65 of solenoids 66 and 67.

At the instant represented in Fig. 36, the valve 300 is in intake position, the pump piston is at the bottom of its stroke, the pump cylinder is full, fixed cam 31 is just ahead of the point of contact with switch 109 and therefore solenoid 66 is about to be energized. In the arrangement of Fig. 36, solenoid 66, when energized, throws the valve 300 into discharge position, in which pump 2 is connected with manifold 31, and also simultaneously throws valve device 301 into open or discharge position, in which discharge lines 8 (with respective ports 57 and passageways 56 and 58) are in registration with passageways 59 in the lower disc. After the solenoid 66 has been energized and valve 300 and valve device 301 thrown into discharge positions, the pump piston travels to the top of its stroke, forcing fluid into filling needles 11 and into the ampuls. The pump piston then starts its return stroke, "suck-back" of fluid from needles 11 occurs, and at the instant when "suck-back" is completed, solenoid 67 is energized, throws valve 300 into intake position and closes valve device 301, and the pump cylinder is again filled from the source of supply.

In the modification of Fig. 36, the positive cut-off of fluid between the manifold and the filling needles, furnished by valve device 301, obviates the need for "goosenecks" in the discharge lines 8. In this respect, the devices of Figs. 3 and 36 are similar.

Figs. 37 and 38 illustrate a modified form of filling needle, in which the central tubular liquid channel 401 is provided with a concentric annular gas channel 402, the latter being in communication with a side-arm 403. A gas such as nitrogen or carbon dioxide may be introduced into side-arm 403 at the same time that liquid is introduced into channel 401, where there is a need for filling ampuls in an inert atmosphere.

Fig. 39 illustrates a modified form of gearing, wherein the meshing gears which transfer the motive power from reduction gears 12 to clutch 16 are beveled gears, rather than spur gears as in Fig. 3. The detail of Fig. 4 also shows gear 14 as a beveled gear.

Pump 2 is illustrated in the drawings as a syringe type of pump, but it will be apparent that any pump having separate intake and discharge cycles may be employed. In the syringe type of pump illustrated in the drawings, the amount of fluid withdrawn by the pump from the

source of supply on the intake cycle, and delivered at the filling needles on the discharge cycle, may be adjusted by altering the length of stroke, as by moving bearing block 28 up or down in radial slot 21. Where a greater adjustment is desired in the amount of fluid delivered, it will suffice to replace the cylinder and the piston of the pump by larger or smaller corresponding parts. By using a series of pistons and cylinders, of different sizes but having interchangeable fittings, the apparatus may be adapted to fill ampuls having a wide range of capacity.

The preferred number of filling needles, as illustrated in the drawings, is sixteen. Ampuls are ordinarily supplied in boxes each containing a gross, arranged in nine rows of sixteen ampuls per row; and in filling the trays (Fig. 20) it will usually be convenient to load the ampuls into nine trays, each containing sixteen ampuls. It is to be understood, however, that a smaller or greater number of ampuls than sixteen may be filled at each loading of the machine, depending upon the number of ampuls which it is desired to fill and for which filling needles are provided.

The function of the equalizing valves 9 is to adjust the rate of flow from each filling needle 11, so that the total amount of fluid displaced by the pump on each discharge cycle will be equally subdivided among the respective filling needles, and so that these will deliver identical amounts of fluid to the respective ampuls. Any convenient form of adjustable flow-controlling valve, e. g. a needle valve, may be used at 9.

The reservoir or source of supply 1 is shown in the drawing (Fig. 1) as a bottle 501, which is replenished by two larger bottles 502 and 503. Bottle 501 may be isolated from the larger bottles, as by clamps 504 and 505, so that either or both of the larger bottles may be replaced without interrupting the continuity of operations. It should be understood, however, that any other form of reservoir or source of supply may be used.

Specific forms of construction and arrangement have been described above for purposes of explanation, but it will be obvious that various modifications may be made within the scope of the invention, which is claimed as follows:

We claim:

1. A device for simultaneously filling a plurality of ampuls which comprises a pump, means for connecting said pump alternately to a source of supply of fluid and to a plurality of discharge means, a plate for carrying a plurality of ampuls and movable between an ampul-loading position in which said ampuls are loaded onto said plate and an ampul-filling position in which said ampuls are respectively presented to said discharge means, a continuously operated source of motive power, a solenoid-controlled pin-operated clutch for intermittently transferring motive power to said pump, and switch means controlling said solenoid, said switch means being closed momentarily once during the cycle of travel of said plate between ampul-loading and ampul-filling positions and being open at all other times during said cycle of travel.

2. A device for simultaneously filling a plurality of ampuls which comprises a source of supply of fluid, a pump having an intake cycle and a discharge cycle and connected to said source, a manifold connected to said pump, a plurality of discharge means connected to said manifold, first valve means controlling passage of fluid between said source and said pump, second

5 valve means controlling passage of fluid between said pump and said discharge means, means synchronized with said pump for keeping said first valve means closed and said second valve means open during the discharge cycle of said pump and a minor portion of its succeeding intake cycle, and means synchronized with said pump for keeping said first valve means open and said second valve means closed during the remainder of said intake cycle.

3. A device according to claim 2 in which each of said discharge means is further provided with an adjustable valve for controlling the rate of discharge from said respective discharge means.

4. A device for simultaneously filling a plurality of ampuls which comprises a reservoir for fluid, an intake valve connected to said reservoir, a pump having an intake cycle and a discharge cycle and connected to said intake valve, a manifold connected to said pump, a plurality of discharge valves connected to said manifold, means synchronized with said pump to keep said discharge valves open and said intake valve closed during the discharge cycle of said pump and a minor portion of its succeeding intake cycle, means synchronized with said pump for keeping said discharge valves closed and said intake valve open during the remainder of said intake cycle, and a plurality of discharge means respectively connected to said discharge valves.

5. A device according to claim 4 in which each of said discharge means is further provided with an adjustable valve for controlling the rate of discharge from said respective discharge means.

6. A device for simultaneously filling a plurality of ampuls which comprises: a source of supply of fluid, a manifold device provided with a chamber and with a plurality of discharge means communicating with said chamber, a pump having an intake cycle and a discharge cycle and connected through a three-way valve alternately to said source and to said chamber, said three-way valve in its first position connecting said pump to said chamber, and in its second position connecting said pump to said source, means synchronized with said pump to keep said valve in its first position during the discharge cycle of said pump and a minor portion of its succeeding intake cycle, and means synchronized with said pump to keep said valve in its second position during the remainder of said intake cycle.

7. A device according to claim 6, in which each of said discharge means is further provided with an adjustable valve for controlling the rate of discharge from said respective discharge means.

8. A device according to claim 6, in which said manifold device is further provided with a plurality of manifold valves controlling passage of fluid between the chamber and the respective discharge means, and means synchronized with said pump to keep said manifold valves open during said first position of said three-way valve and closed during said second position of said three-way valve.

9. A device for simultaneously filling a plurality of ampuls which comprises: a pump having an intake cycle and a discharge cycle; a valve connected to said pump and comprising a fixed lower disc provided with a manifold, an intake passage leading thereto and a plurality of discharge passages leading therefrom, and an upper disc concentric with and rotatable on said lower disc between an intake position and a discharge position and provided with an intake port regis-

tering with said intake passage in intake position but not in discharge position, and a plurality of discharge ports respectively registering with said discharge passages in discharge position but not in intake position; means synchronized with said pump to rotate the upper disc to discharge position at the end of the intake cycle of said pump; and means synchronized with said pump to rotate the upper disc to intake position shortly after the beginning of the intake cycle of said pump.

10. A device for simultaneously filling a plurality of ampuls which comprises: a source of supply of fluid; a pump having an intake cycle and a discharge cycle; a valve device comprising a fixed lower disc provided with a chamber and with an intake passage, a pump port and a plurality of discharge passages communicating with said chamber, and also comprising an upper disc concentric with an rotatable on said lower disc between an intake position and a discharge position and provided with an intake port registering with said intake passage in intake position but not in discharge position and a plurality of discharge ports registering respectively with said discharge passages in discharge position but not in intake position; said intake port being connected to said source of supply, said pump port being connected to said pump and said discharge ports being respectively connected to a plurality of discharge means; means synchronized with said pump to rotate said upper disc to discharge position at the end of the intake cycle of said pump; and means synchronized with said pump to rotate said upper disc to intake position shortly after the beginning of the intake cycle of said pump.

11. A device according to claim 10 in which each of said discharge means is further provided with an adjustable valve for controlling the rate of discharge from said respective discharge means.

12. A device for simultaneously filling a plurality of ampuls which comprises a source of supply of fluid, a pump having an intake cycle and a discharge cycle and connected to said source, a manifold connected to said pump, a plurality of discharge means connected to said manifold, first valve means controlling passage of fluid between said pump and said source, second valve means controlling passage of fluid between said pump and said discharge means, a first solenoid means for simultaneously closing said first valve means and opening said second valve means, a second solenoid means for simultaneously opening said first valve means and closing said second valve means, a first switch which, when closed, energizes said first solenoid means, a second switch which, when closed, energizes said second solenoid means, a fixed cam means set to close said first switch at the end of the intake cycle of said pump, and an adjustable cam means set to close said second switch at an adjustable short interval after the beginning of the intake cycle of said pump.

13. A device for simultaneously filling a plurality of ampuls which comprises: a source of supply of fluid; a pump having an intake cycle and a discharge cycle; a valve device comprising a fixed lower disc provided with a chamber and with an intake passage, a pump port and a plurality of discharge passages communicating with said chamber, and also comprising an upper disc concentric with and rotatable on said lower disc between an intake position and a discharge po-

sition and provided with an intake port registering with said intake passage in intake position but not in discharge position and a plurality of discharge ports registering respectively with said discharge passages in discharge position but not in intake position; said intake port being connected to said source of supply, said pump port being connected to said pump and said discharge ports being respectively connected to a plurality of discharge lines, each of said discharge lines being provided with an adjustable valve to regulate the rate of discharge therefrom; a first solenoid means for throwing said upper disc into discharge position; a second solenoid means for throwing said upper disc into intake position; a first switch which, when closed, energizes said first solenoid means; a second switch which, when closed, energizes said second solenoid means; a fixed cam means set to close said first switch at the end of the intake cycle of said pump; and an adjustable cam means set to close said second switch at an adjustable short interval after the beginning of the intake cycle of said pump.

14. A device for simultaneously filling a plurality of ampuls which comprises: a source of supply of fluid; a pump having an intake cycle and a discharge cycle; a valve device comprising a fixed lower disc provided with a chamber and with an intake passage, a pump port and a plurality of discharge passages communicating with said chamber, and also comprising an upper disc concentric with and rotatable on said lower disc between an intake position and a discharge position and provided with an intake port registering with said intake passage in intake position but not in discharge position and a plurality of discharge ports registering respectively with said discharge passages in discharge position but not in intake position; said intake port being connected to said source of supply, said pump port being connected to said pump and said discharge ports being respectively connected to a plurality of discharge lines, each of said discharge lines being provided with an adjustable valve to regulate the rate of discharge therefrom; means synchronized with said pump to keep said upper disc in discharge position during the discharge cycle of the pump and a minor portion of its succeeding intake cycle; means synchronized with said pump to keep said upper disc in intake position during the remainder of said intake cycle; a plate for carrying a plurality of ampuls and vertically reciprocable between an ampul-loading position in which said ampuls are loaded onto said plate and an ampul-filling position in which said ampuls are respectively presented to said discharge means; and means coordinated with the movement of said plate to limit said pump to a single discharge during a single stay of said plate in ampul-filling position.

15. A device for simultaneously filling a plurality of ampuls which comprises a pump, means for connecting said pump alternately to a source of supply of fluid and to a plurality of discharge means, a plate for carrying a plurality of ampuls and movable between an ampul-loading position in which said ampuls are loaded onto said plate and an ampul-filling position in which said ampuls are respectively presented to said discharge means, a continuously operated source of motive power, a clutch for intermittently transferring motive power to said pump, and means responsive to the movement of said plate to limit said clutch to a single cycle of operation for each

traverse of said plate between successive ampul-
filling position.

16. A device for simultaneously filling a plu-
rality of ampuls which comprises a source of
supply of fluid, a manifold having a capacity
at least equal to the combined capacity of said
plurality of ampuls, a pump having an intake
cycle and a discharge cycle and connected al-
ternately to said source and to said manifold, first
discharge means connected to said manifold, first
cut-off means controlling passage of fluid be-
tween said source and said pump, second cut-off
means controlling passage of fluid between said
pump and said discharge means, and means syn-
chronized with said pump for keeping said first
cut-off means closed and said second cut-off
means open during the discharge cycle of said
pump and a minor portion of its succeeding in-
take cycle and for keeping said first cut-off means
open and said second cut-off means closed dur-
ing the remainder of said intake cycle.
